UNITED STATES PATENT OFFICE

115,712

DESIGN FOR A SPRING SASH BALANCE HOUSING

Albert Herman Kersting, deceased, late of Los Angeles, Calif., by Nelle Frances Kersting, Los Angeles, Calif., executrix

Application May 4, 1939, Serial No. 84,795

Term of patent 14 years

To all whom it may concern:

Be it known that Albert Herman Kersting, deceased, late a citizen of the United States and resident of Los Angeles, in the county of Los Angeles and State of California, did invent a new, original, and ornamental Design for Spring Sash Balance Housings, of which the following is a specification, reference being had to the accompanying drawing, forming part thereof.

Fig. 1 is a front elevational view of the spring sash balance housing showing the new design.

Fig. 2 is a rear elevational view of the spring sash balance housing.

Fig. 3 is a side elevational view of the spring sash balance housing.

What is claimed is:

The ornamental design for a spring sash balance housing, as shown.

NELLE FRANCES KERSTING,
Executrix of the Last Will and Testament of
Albert Herman Kersting, Deceased.
